FILLING MACHINE VALVE

Wilbur H. Bulcao, Pittsburgh, Pa., assignor to
 Horix Manufacturing Company, Pittsburgh,
 Pa., a corporation of Pennsylvania

Application March 1, 1952, Serial No. 274,463

5 Claims. (Cl. 226—116)

1

This invention relates to filling machine valves, and more particularly to those used in machines for filling wide-mouth containers at high speed.

Container filling machines are well known in which containers are carried on supports that lift them up to valves around the bottom of a rotating tank. It generally is desirable to operate these machines as fast as possible, some of them filling several hundred containers per minute. Machines that fill wide-mouth containers are capable of operating this fast, except that when they fill to a high filling height, particularly with hot products, difficulty is experienced in separating the containers from the rubber seals or gaskets which their upper ends engage. This is due to the formation of a partial vacuum in the containers which causes them to break away with a jerky motion or, in some cases, even makes it necessary to exert pressure on the outside of the containers to break them away from the gaskets. This interferes with the smooth operation of the machine and also causes the containers to spill liquid. If the containers are made of glass, it may even result in their breakage. To overcome this difficulty, the gaskets have been formed in different ways intended to break the vacuum as soon as the container supports start to descend. For example, the sealing surfaces of the gaskets have been provided with radial ribs that press the containers away from the sealing surfaces as soon as the pressure of the containers against them is reduced by the descending supports. However, in such cases the container lips soon wear through the ribs and make them ineffective.

It is among the objects of this invention to provide a high speed filling machine valve from which wide-mouth containers will quickly separate as soon as their supports start to descend, and which includes a sealing gasket that may be made of uniform thickness throughout, with no projections or openings in its sealing surface.

In accordance with this invention, a resilient gasket surrounds the lower end of the vertical filling tube of a filling machine valve and has a lower sealing surface that is adapted to be engaged by the lip of an empty container which is raised up against it by the container support. Means is provided above the gasket for constantly pushing only a portion of it downward. Consequently, when the container support starts to descend after the container has been filled, this downwardly urged portion of the gasket will push the container away from some of the sealing surface of the gasket and thereby break any vacuum

2

in the container which otherwise might hold the container against the gasket.

The preferred embodiment of the invention is illustrated in the accompanying drawings, in which Fig. 1 is a side view of my filling valve, with parts shown in section and with a container lip touching only the downwardly pressed portion of the sealing gasket; Fig. 2 is a similar view, but with the valve opened by the raised container; and Fig. 3 is a horizontal section taken on the line III—III of Fig. 1.

The valve illustrated is only one of several that may be screwed into a ring of openings in the bottom of the rotating tank of a conventional automatic filling machine. This valve has a vertical filling tube 1 that is threaded at its upper end for screwing into the bottom of such a tank. The lower end of the tube is provided at one side with a liquid outlet 2. The opposite side of the tube is provided with an air vent 3 that communicates with the lower end of a vent tube 4 extending up through the filling tube to a point above the level of the liquid in the tank in a well known manner. Screwed onto the closed lower end of the filling tube is a valve seal 6 that projects radially from the tube for a short distance. The valve is normally closed by a sleeve 7 which is slidably mounted on the tube. The lower end of the sleeve is pressed against the seal 6 by means of a coil spring 8 that encircles the upper portion of the filling tube.

The valve sleeve has a threaded portion, on which a supporting member or collar 10 is screwed. The bottom of the collar is provided with a circular recess 11, and a resilient gasket 12 of rubber or the like that tightly encircles the sleeve is confined in this recess. The lower surface of this gasket forms a sealing surface which is engaged by the lip of an empty wide-mouth container 13 every time such a container is raised by the support 14 on which it rests. As is well known in this art, the container is raised against the gasket not only to press its lip against the sealing surface, but also to push the valve sleeve upward on filling tube 1 in order to open the valve outlet 2 and air vent 3, as shown in Fig. 2, so that the container will be filled. As the container support descends with the filled container, coil spring 8 pushes valve sleeve 7 downward until it engages the seal 6 on the lower end of the filling tube to close the valve. Further downward movement of the support is supposed to lower the filled container away from sealing gasket 12, but heretofore the container often has not separated from such a smooth surface gasket or it has stayed

against it for a moment after it should have separated. This is due to a partial vacuum being formed in the container, especially when the machine is operated at high speed or the filling material is hot.

It is a feature of this invention that the container is pushed down away from most of the sealing gasket 12 after the container has been filled, thereby breaking any vacuum that might hold it against the gasket. This is accomplished by providing means for always pressing a small portion of the gasket downward, so that the moment the container support starts to descend, the container will be pushed downward with its support until some of its lip separates from the sealing gasket. There is then nothing to hold the container against the gasket. The downward pressure on the sealing gasket is produced by a pressure member located between the top of the gasket and the upper wall of the collar recess 11. To compensate for wear on the gasket and to permit variable downward pressure for various size containers, it is desirable to exert adjustable pressure downward on the pressure member, such as by a coil spring. This can be done conveniently by forming the pressure member as a head 16 on the lower end of a stem 17 that extends loosely up through a vertical passage 18 through a lateral enlargement in collar 10. A coil spring 19 encircles the stem and is compressed between its head and a shoulder 21 near the upper end of the passage. The upper end of the stem extends above the collar and is threaded and provided with lock nuts 22 which can be screwed up or down the stem to control the distance that it can be moved downward by the spring. It also is desirable to enlarge the lower end of passage 18 to form a recess 23 that will receive the pressure head when the sealing gasket is pushed upward by a container.

In the use of this valve, the support 14 lifts a container up against sealing gasket 12 when all parts of the valve are in the position shown in Fig. 1. As is also shown in that figure, the upper edge or lip of the container first engages the small portion of the sealing gasket that is pressed downward by pressure head 16. Continued upward movement of the container presses its entire lip up into the sealing gasket, as shown in Fig. 2, and thereby pushes the pressure head and stem 16 upward in collar passage 18. The top of the container then is completely sealed by the gasket. As the container continues to move upward, it opens the valve as has been explained previously so that the container can be filled with the material flowing down through filling tube 1 and out of outlet 2. As soon as the container is filled, the support 14 starts to descend. This reduces the pressure of the container against gasket 12, whereupon the downward pressure of head 16 against the top of the gasket presses the underlying portion of the gasket downward in collar 10 and thereby holds the container against its support, even though a partial vacuum in the container may attempt to hold the container up against the gasket. The downwardly moving portion of the gasket compels the container to follow its support downward until the opposite side of the container separates from the gasket. This breaks any vacuum that may have been present so that the container thereafter will descend with the support by gravity.

Due to the fact that the sealing surface of gasket 12 originally is flat, there are no vacuum-breaking projections to be cut or worn away by

the upper edges of the containers. If the downwardly pressed area of the sealing surface tends to wear more rapidly than the remaining area, the gasket can be rotated a few degrees in the collar occasionally to bring a new area of the sealing surface beneath the pressure head.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

II-claim:

1. In a high speed filling machine, the combination with a vertically movable container support, of a valve comprising a vertical filling tube, a resilient gasket surrounding the lower end of said tube and having a lower sealing surface adapted to be engaged by the lip of an empty container raised up against it by said support, and means above the gasket constantly pushing only a portion of the gasket downward to deform its sealing surface, said means exerting sufficient downward pressure on said portion to cause it to push the container straight down away from some of said sealing surface as the container support moves down away from the gasket after the container has been filled, whereby to admit air between the gasket and container so that the container will separate from the gasket and remain seated on the descending support.

2. In a high speed filling machine, the combination with a vertically movable container support, of a valve comprising a vertical filling tube, a resilient gasket surrounding the lower end of said tube and having a lower sealing surface adapted to be engaged by the lip of an empty container raised up against it by said support, a supporting member engaging most of the top of the gasket, and a pressure member between said supporting member and a portion of the top of the gasket for pressing the underlying portion of the gasket downward, said pressure member exerting sufficient force on said underlying portion to cause it to push the container straight down away from some of said sealing surface as the container support moves down away from the gasket after the container has been filled, whereby to admit air between the gasket and container so that the container will separate from the gasket and remain seated on the descending support.

3. In a high speed filling machine, the combination with a vertically movable container support, of a valve comprising a vertical filling tube, a resilient gasket surrounding the lower end of said tube and having a lower sealing surface adapted to be engaged by the lip of an empty container raised up against it by said support, a supporting member engaging most of the top of the gasket, a pressure member between said supporting member and a portion of the top of the gasket, and a spring pressing down on said pressure member to push the underlying portion of the gasket downward, said spring being strong enough to cause said underlying portion to push the container straight down away from some of said sealing surface as the container support moves down away from the gasket after the container has been filled, whereby to admit air between the gasket and container so that the container will separate from the gasket and remain seated on the descending support.

4. In a high speed filling machine, the combination with a vertically movable container support, of a valve comprising a vertical filling tube, a resilient gasket surrounding the lower end of said tube and having a lower sealing surface adapted to be engaged by the lip of an empty container raised up against it by said support, a supporting member engaging most of the top of the gasket, said member being provided at one side with a vertical passage through it, a stem vertically movable in said passage, a head on the lower end of the stem engaging the top of said gasket, and a coil spring surrounding said stem and pressing it and the head downward to depress a portion of said sealing surface, said spring being strong enough to cause said portion of the sealing surface to push the container straight down away from the rest of said sealing surface as the container support moves down away from the gasket after the container has been filled, whereby to admit air between the gasket and container so that the container will separate from the gasket and remain seated on the descending support.

5. In a high speed filling machine, the combination with a vertically movable container support, of a valve comprising a vertical filling tube, a sleeve slideable vertically on the tube, an annular member surrounding the sleeve and rigidly mounted thereon, a resilient gasket surrounding the lower end of said sleeve in engagement there-

with and with said member, the gasket having a lower sealing surface adapted to be engaged by the lip of an empty container raised up against it by said support, said annular member being provided at one side of the sleeve with a vertical passage, a stem vertically movable in said passage, a head on the lower end of the stem engaging the top of said gasket, a coil spring surrounding said stem and pressing it and the head downward to depress a portion of said sealing surface, and vertically adjustable means on the stem above the spring for controlling the distance the head can move downward, the spring being compressed sufficiently to cause said portion of the sealing surface to push the container straight down away from the rest of said sealing surface as the container support moves down away from the gasket after the container has been filled, whereby to admit air between the gasket and container so that the container will separate from the gasket and remain seated on the descending support.
